Primary Examiner — Cynthia Ramirez*Assistant Examiner* — Llorellys Martinez-Rivera(57) **CLAIM**

The ornamental design for an oral care implement, as shown.

DESCRIPTION

FIG. 1 is a right front perspective view of an oral care implement showing our new design;

FIG. 2 is a left rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.
